VEHICLE LAMP

David M. Morgenstern, Cleveland, Ohio

Application February 15, 1950, Serial No. 7,941

Term of patent 7 years

(Cl. D48—32)

To all whom it may concern:

Be it known that I, David M. Morgenstern, a citizen of the United States, residing at Cleveland, county of Cuyahoga, and State of Ohio, have invented a new, original, and ornamental Design for Vehicle Lamp, of which the following is a specification, reference being had to the accompanying drawing, forming part hereof, wherein Fig. 1 is a front elevational view of a vehicle lamp showing my new design; and Fig. 2 is a side elevational view thereof.

The dominant features of my design reside in the portions shown in solid lines in the drawing.

I claim:

The ornamental design for a vehicle lamp, as shown and described.

DAVID M. MORGENSTERN.
